UNITED STATES PATENT OFFICE.

LUTHER C. CROWELL, OF SOUTH WELLFLEET, MASSACHUSETTS, AS-SIGNOR OF ONE-THIRD TO ROBERT W. HOWARD AND CHARLES F. A. SMITH, OF BOSTON, MASSACHUSETTS; LUTHER F. CROWELL ADMINISTRATOR OF SAID LUTHER C. CROWELL, DECEASED.

LABELING-MACHINE.

SPECIFICATION forming part of Letters Patent No. 787,876, dated April 18, 1905.

Application filed September 22, 1902. Serial No. 124,383.

To all whom it may concern:

Be it known that I, LUTHER C. CROWELL, a citizen of the United States, residing at South Wellfleet, county of Barnstable, and State of Massachusetts, have invented certain new and useful Improvements in Labeling-Machines, fully described and represented in the following specification and the accompanying drawings, forming a part of the same.

The object of this invention is to provide means by which labels can be accurately, rapidly, and economically applied to bottles and similar articles, and while certain features of the invention are adapted to the application of what are known as "body-labels" the invention relates more especially to that class of labels known as "neck-labels," which are applied to the conical or neck portions of bottles and similar articles. These labels are usually made in attractive designs, ornamental in effect, and their conspicuous position makes them an important advertising medium. The majority of bottles are in the form of a cylinder, the neck tapering therefrom to the nose or stopper end at a more or less acute angle or curve. While several mechanical combinations have been devised by which labels are attached to the body of such bottles and to such parts as are of cylindrical shape, or substantially so, with more or less rapidity and accuracy, the application of labels to the neck or conical portions of the bottle by machine has been found more difficult of attainment, so that the expense of attaching such labels has prior to my invention prevented their general use.

For a full understanding of the invention a detailed description of a labeling-machine embodying all the features of the invention in their preferred form will now be given in connection with the accompanying drawings, forming a part of this specification, and the features forming the invention then specifically pointed out in the claims.

In the drawings, Figure 1 is a plan view of a preferred form of mechanism embodying

the invention, certain parts being omitted for better illustration, and showing by dotted and by full lines two different positions. Fig. 2 is a side elevation of the upper portion of the machine shown in Fig. 1 as indicated by the direction-arrow 2' of Fig. 1. Fig. 3 is a plan view similar to Fig. 1, showing another position and also that of a bottle receiving a neck-label, parts of the mechanism being omitted for the purpose of illustration. Fig. 4 is a front elevation of the parts shown in Fig. 2 looking in the direction of the arrow 3' in Fig. 1. Fig. 5 is a plan view similar to Fig. 2, showing the application of the mechanism to the applying of neck-labels only, different positions of the label being shown in dotted lines, while several parts are omitted for purposes of illustration. Fig. 6 is a plan view similar to Fig. 1. Fig. 7 is a side elevation, partly in section, taken on the line 6' of Fig. 6. Fig. 8 is a side elevation of the machine looking to the right of Fig. 7. Fig. 9 is a horizontal section on line 9' of Fig. 8. Figs. 10 and 11 are side elevations of the label-grippers, showing different positions of the same. Fig. 12 is a plan view of Fig. 11. Fig. 13 is a partial plan view of the label-smoothing device. Fig. 14 is a side elevation of the same. Fig. 15 is a detail section of the bottle-nose holder. Figs. 16 and 17 are views showing other forms of bottle-nose holders as applied to different forms of bottle-necks. Fig. 18 is a plan view of the mechanism shown in Fig. 16. Figs. 19, 20, and 21 are side elevations of different-shaped bottles and their relation to the neck-labels and the point or center of rotation of the bottle, as indicated by dotted lines 5'. Figs. 22 to 25 are front elevations of various-shaped bottles with neck or body labels attached. Figs. 26 and 27 are rear elevations of Figs. 22 and 23, respectively, with neck-labels attached. Figs. 28 and 29 are front and rear elevations, respectively, of an ordinary soda-bottle with neck and body labels attached. Figs. 30 and 31 are enlarged front and end elevations of the mechanism shown

in Fig. 2. Fig. 32 is a plan view of a modified form of mechanism, in which the pasting device is driven from the roller L' . Fig. 33 is a rear elevation of the same. Fig. 34 is 5 another modified form, in which the pasting device is driven from the roller j^2 through the shaft S' . Figs. 35 to 36 are details thereof, showing different positions of the actuating mechanism. Fig. 37 is a detail of part of the 10 modified form of mechanism shown in Fig. 34.

The present application shows the invention adapted to the application of a body-label and then a neck-label, or vice versa, requiring two 15 presentations of the bottle; but it is obvious that the invention includes the application of either class of labels exclusively.

In the present application preference is given to the use of labels in block form, and they may be so prepared by holding a sufficient 20 number firmly in accurate alinement and one end of the pack then gummed and allowed to dry, and for convenient handling they may be bound together by a band of paper, which is removed when the pack is placed 25 in the machine. In this block form the labels are maintained in a uniform position in the machine, and it is possible, if desired, where the gummed end of the block is the leading end, to avoid the use of grippers, 30 while in any case the gummed end offers no substantial resistance to the separation of the top label from its block. It is desirable, however, that the operator before using a fresh block should hold it by its gummed end and 35 "thumb" the ungummed end freely to insure the separation of the labels singly in the machine. If it is desired to use loose labels not prepared in the block form just described, "holding-grippers" similar to those shown in 40 Figs. 10 to 12 may be located so as to control both ends of the label and operated to release the same, as described hereinafter.

Referring now to Figs. 1 to 7 of the drawings, in which similar letters of reference indicate corresponding parts, the framework A 45 supports a fixed central vertical shaft B, which forms a bearing for the hollow shaft D. The shaft D supports at its upper end a cup-shaped boss E, to which is secured the rotating table

50 P. The shaft D has secured to it a collar, from which extends outwardly two adjustable arms G, which support the block of labels F and their feeding devices. The shaft D is driven from a pulley e' , secured to the lower end of 55 said shaft.

In the preferred form the paste is applied to the labels by a paste-roller L, mounted in a frame R, which receives paste from a fountain Q, secured to the brackets S by screws 60 or in any suitable manner. The roller L is provided with an ordinary "docto-blade," adjustably secured to the frame by adjusting-screws a^2 to regulate the flow of paste. A disk T, secured to the shaft of paste-roller L, 65 engages with and is driven by contact with

the raised portion U of table P to rotate the paste-roller L. The nose of the bottle is supported by a cap V, secured to a bent arm W, pivotally mounted on the top of the shaft B by a screw C and normally held in position by a spring d' , as shown in Fig. 15. When it is desirable, as in some cases, that this cap V be adjusted, both vertically and horizontally, the construction shown in Figs. 16 and 17 is preferred. In this construction the arm W of Fig. 15 is U-shaped, and one end of it pivots on the upper end of the shaft B by pivot C and its other end is tapped to receive the bolt d for adjustably securing a slotted plate X, which carries at one end the corrugated-faced hub J', which is engaged by a second corrugated hub, carried by a slotted plate Y, said hubs being held in engagement with each other by a bolt and tightening-nut J², by which the plate Y may be positioned at any desired angle. The plate Y is provided with a slot through which passes a bolt b, which enters and secures to the plate Y a block Z, to which is pivoted at c the revolving cap V. The cap is held in its normal position by spring d' , before mentioned.

In the following description of the operation of the mechanism the remaining parts will be more fully pointed out and their functions more fully described. In describing parts which are in duplicate one set will be described in detail, it being understood that the description applies to both, the same reference-letters being used for corresponding parts in the two sets.

As shown in Figs. 1 to 4, neck-labels and body-labels are applied alternately by the same machine. In this construction an arched brace e forms a part of framework A and supports the swinging arm g by means of stud f. This arm in turn supports the shaft i, which carries pinion j at one end and forms the shaft of roller n at its other end. The arm g also carries the frame m, which supports rollers p n o. The other end h of arm g is bent at a right angle and carries devices which aid in starting and stopping the movement of said arm. The rollers p n o are driven in unison by gears b' b² b³, which serve to drive a belt q.

Labels prepared in the block form, as described, are placed in their respective receptacles H' in the table P, a block of neck-labels and a block of body-labels diametrically opposite each other.

In the mechanism now being described the labels are placed with their free or ungummed ends leading and the top label slightly below paste-roller L, the labels being held in this position by the supporting-block H, (see Fig. 7,) which corresponds in outline with the respective labels and are held in position by rod I and spring J and locking-screw K until the movement of table P brings the labels under the paste-roller L, when the arm M, secured to the locking-screw K, engages the

stationary cam N, turning the screw K to release the rod I, when the spring J will force the labels into contact with the under side of paste-roller L. The ductor-blade having 5 been regulated by its screws a^2 a^2 paste is applied to the top label as the label passes under the paste-roll L.

As the arm M of screw K leaves cam N the spring s, which has previously been placed 10 under tension by the arm M, acts to turn the screw K into binding contact with rod I, holding the labels F in position with the top label slightly above the guides g'. These guides are adjustably secured to the table P by 5 brackets f² and are preferably provided with a spring s' (see Figs. 10, 11, 13, 14) at their upper ends, which binds slightly against the sides of the top labels.

To insure a smooth and uniform presentation to the paste-roller and to the bottle O, grippers p' are located and operated to control the leading free ends of the labels. (See Figs. 10 and 12.) A shaft r', mounted in brackets s², secured to table P, carries arms 5 c', in which are mounted the rock-shaft q', to which the grippers p' are fixed. The ends of the rock-shafts r' q' are provided with arms r² q² for a purpose hereinafter referred to. The grippers p' will be in the position shown 10 in full lines in Fig. 10 as the labels approach and pass under the paste-roller L, insuring their smooth passage.

Assuming the first operation to be the application of a body-label, the bottle O will be 5 placed in the position shown in full lines in Figs. 1, 2, and 4 within the arms o', which are attached to a shaft mounted in the hollow shaft of roller o, the bottom of the bottle resting against a stop a', which is fixed to the frame 10 m of arm g. A slight pressure of the bottle into the bight of belt q, which belt passes under the roller n, over and around the rollers p o, will cause it to be rolled over the label and into the position immediately beneath roller o. (See Figs. 1 and 4.) The arms o' will insure the true position of the bottle on the label. The grippers p' will now be released from engagement with the labels by the engagement of levers r² q² 15 with stationary studs secured to brackets L L', (see Figs. 5 to 8,) which are fixed to the framework A. As the grippers pass under the bottle in the position shown in Figs. 11, 12 motion is given to the belt q by means of the pinion j engaging with stationary rack k, as follows: A stud y is fixed to the table P or its raised portion U, so as to engage the curved lever w, journaled in the end h of the arm g, when the belt-carrying rollers p n o are 20 above the body-label. To avoid a blow, the rock-shaft r, pivoted in the arm h, is provided on one end with a curved lever w and on the other end with two levers x u, the lever u being provided with a stud which engages in a cam-path t in the rack-frame k. When the

body-label is nearly in alinement with the belt q, the stud y engages the lever w and starts the arm h gradually into motion, controlled by the lever u and the cam-path t. (See 25 Figs. 30, 31.)

When the body-label is in alinement with the belt q, the arm g has attained the speed of the body-label and maintains it until the bottle O has been rolled by the belt q over the label and attached the label to it, when it 30 will be in the position shown in dotted lines in Fig. 1 and free to be removed by the operator. At this time the cam-path t will have caused the lever w to leave the stud y, when the spring l will turn the pinion j, shaft i, and cause the arm g to return to its normal position. To insure the smooth presentation of the labels which have just passed under the bottle, a smoothing-bar u² is provided fixed to a shaft u', which is mounted in arm f', pivoted to arm G and maintained by a spring in a normal position at the rear of the labels F. (See Figs. 13, 14.) As this is the gummed end of the labels, they remain true, while the lever Z' of lever f' engages with stationary arm z, (see Figs. 6 to 9,) moving the bar u² forward and engaging a cam t', fixed to the guides g', said cam raising the bar u² slightly to clear the ends of the labels F, when the bar u² will be pressed down by its springs, 35 and the onward motion of the arm f' will cause it to smooth the labels down to their free ends.

When the bar u² has thus smoothed the labels down, the stationary studs secured to the brackets L² will, through the levers q³ 40 r² and springs q², cause the grippers p' to close upon the free ends of the labels, as shown in Fig. 6, and the operation will be repeated with each block of labels as the table P revolves. The body-label having been applied as described and the arm g returned to its normal position, the bottle O will be reversed by the operator, its nose inserted in the cap V and held under slight hand-pressure against the same, with its full weight upon the labels, 45 when the top label will be rolled off the top of the pile and around the neck of the bottle and separated from the pile at its glued end. (See Fig. 3.) In this manner body and neck labels may be applied to bottles and similar articles rapidly and accurately. In the machine just described it will be understood that any other suitable pasting device may be employed and that the rollers n o p may be mounted in adjustable bearings to accommodate bottles 50 of different sizes, if desired.

When it is desired to apply neck-labels exclusively, the brace e may be removed, together with the arm g and the rack k, and only neck-labels supplied, or, if desired, the "grippers" and "smoothing-bar," with all their connections, may be removed, when the labels should be reversed and placed with the gummed end leading. In this case if the table P be moved continuously the operator will insert 55

the bottle-nose in the rear of the labels, which is now their free end, and move its body lightly forward in rolling contact with the top label. The cap V will then swing slightly on its pivot C on the shaft B, but will be returned to its normal position by the spring d'. If preferred, however, the table P may be moved intermittently and brought to rest after a label has passed under the paste-roller, when the bottle 5 will be inserted within the control of the cap V, as just described, and rolled over the labels, the cap V being so adjusted as to form a center around which travels that portion of the bottle which comes in contact with the label.

10 When it is desired to label bottles of various sizes and shapes, it is preferred that the mountings of the cap V should be similar to those shown in Figs. 16, 17, while in some instances, where the bottle is of a shape similar 15 to that shown in Figs. 16, 17, 18, it may be necessary to modify the shape of the label-carrying table P; but in the majority of cases the bottles so nearly average a uniform size that it is found more convenient to have an arm to 20 support the cap V for each different shape.

25 Fig. 32 shows in plan view a modified form of the invention, and Fig. 33 a rear elevation of the same, the label-carrying table P being mounted substantially as previously described, with the labels held and controlled in the same manner, the motion of the table P being intermittent. The table P carries on its raised portion teeth D', which engage with a pinion S⁸ on shaft S⁴, which in turn carries 30 miter-gear S⁵, which engages with and drives miter-gear S⁶, fixed to the shaft of paste-roller L'. Bracket S, bolted to the framework A, holds the framework R, which supports the paste-rollers L' and j² and also the paste-fountain Q. A distributing-roller j³ is mounted 35 in boxes which travel on rods C' C', said rods being held in brackets B', which are bolted to the framework A at one of their ends and to the frame R at their other ends. Links h' connect the brace j' and the boxes which support the roller j³ with the arm A', which is mounted loosely on rock-shaft n', held in bearings v', bolted to the framework A. A toothed segment F' is fixed to the shaft n' and engages 40 with a miter-gear E', loosely mounted on the shaft D and supported in place by collar w'. A pawl y², pivoted to the hub of arm G, fixed to the hollow shaft D, communicates motion from the gear E' to the hollow shaft D. A lever 45 x', also fixed to the shaft n', carries at one end a stud x², which engages with the hooked portion of arm A'. A reciprocating motion is given to the lever x' by any suitable driving means, which may be connected with the stud 50 y' or by a foot-treadle fixed to shaft n'. A brace k', forming part of the framework A, carries two fixed studs l' l'. A lever m' (see Figs. 35, 36) is pivoted to the arm A', its long arm resting upon the stud l', its short 55 arm upon the stud l'. The spring x³, attached to the framework A and the boss of arm A', holds the parts in this position, as shown in Fig. 35. The labels F having been placed in position in the machine with their gummed ends leading and the guides g' having been 60 adjusted to secure them in such position, the first forward movement of the lever x' will cause the segment F', miter E', and the table P to turn in the direction of the arrow a one-half revolution, thus imparting motion to the 65 paste-rollers through the gear D' engaging with a pinion S⁸ on the vertical shaft S⁴, the miter S⁵ on the same shaft engaging the gear S⁶ on the shaft of the roller L' and through gears to the roll j². The customary ductor-blade may be applied to roller L' to regulate the flow of paste, which will be transferred from L' to roller j² and by it to roller j³. The arm A', with the paste-roller j³, will remain in their first position until the table P 70 makes nearly a one-quarter revolution or arrives at the position shown by full lines in Fig. 32, when the stud x² of lever x' will pass under the long arm of lever m', raising it and causing its short arm to pry against the stud l', gradually starting the arm A' forward until the stud x² of arm x' meets the vertical portion of arm A', when the two will move forward simultaneously. (See Fig. 36.) This movement will cause the paste-roller j³ to be 75 carried forward just in advance of the leading ends of the labels F to the end of the motion, when the table P comes to rest and the spring-pawl D², pivoted to the frame A, engages with the recess D³ in the raised portion 80 U of the table P, holding said table stationary during the return motion of lever x'. On this return movement the spring x³, fixed to the arm A' and framework A, will cause it to follow the lever x', which will result in the 85 paste-roller j³ being carried over in contact with and paste the top label of the block of labels F. On the return motion of arm A' and its paste-roller j³ the table P and labels F remain in the position shown by dotted lines 90 in Fig. 32.

95 Figs. 34 and 37 show another modified form in which the pasting device is driven from the roller j² through the shaft S', and in this form the gear D' engages with the pinion S⁷ on the vertical shaft S', the miter S² on the same shaft engaging the gear S⁸ on the shaft of the roll j² and through gears on the opposite side of the roll j² to paste-roller L'.

The height of the labels is determined by 100 the action of devices similar to those heretofore described, excepting that the conical-shaped roller L will not serve as a paste-roller, but only as a gage-roller, and will be placed so that the block of labels will pass under it and their height be determined just after a top label has been applied to a bottle, the height of said gage-roller corresponding to that of the paste-roller j³. The table P having come to rest, the operator will insert 105

the bottle-nose in the cup V, as shown in dotted lines of bottle O³, Fig. 32, the free ends of the labels being nearest the bottle. With a slight pressure against the cap V and allowing the full weight of the bottle to rest upon the label the operator will swing it by its bottom over the labels to the position shown in Fig. 32 by dotted lines of bottle O⁴, when the top label will have been wrapped about the neck of the bottle and separated from its block. The bottle will then be removed, when the cap V will return to its normal position for the next bottle.

In some instances, where it is desired to label bottles as shown in Figs. 16 to 18, the boss E, which connects table P with the shaft D, should be of such dimensions as will give sufficient room between the top of stationary shaft B and table P to permit the passage of the nose of the bottle during the application of the label. It will also be observed that the section W (see Figs. 16 and 17) might be specially made for use in such cases with its ends sufficiently wide apart for its top arm or end to receive or hold the parts X Y Z V in the position shown in Fig. 17.

When a label is attached to the shoulder of a bottle of the style shown in Fig. 16, one set of labels only can conveniently be carried by table P. The gummed ends of the labels will be placed leading and the first to enter under the pasting device. The top label having been pasted and the table brought to rest, the operator will insert the bottle-nose within the cap V and roll the body over the label, beginning at its free end, as previously described, when the bottle will be removed, another revolution of the table made by hand or otherwise, another bottle inserted, and the operation repeated, resulting in the accurate and rapid application of such labels.

It will be understood that many modifications may be made in the mechanism shown without departing from my invention, and I am not to be limited to the specific form or arrangement of the devices illustrated.

What I claim is—

1. A horizontal label-supporting device in combination with a rotating table having a central device mounted at a fixed point for holding a bottle-nose during rotation of the bottle in contact with the label, substantially as described.

2. A label-supporting device in combination with a rotating table having a central device mounted at a fixed point for holding a bottle-nose during rotation of the bottle, said device being mounted to rotate to permit the bottle to be moved longitudinally of the label as the bottle is rotated, substantially as described.

3. A horizontal label-supporting device in combination with a rotating table having a central device mounted at a fixed point for holding a bottle-nose during rotation of the bottle in contact with the label, and means for

applying adhesive material to the label, substantially as described.

4. A rotating table having a supporting device for holding a pile of labels in combination with a central device mounted at a fixed point for holding a bottle-nose during rotation of the bottle in contact with the top label, and an automatic label-supply mechanism for advancing the pile of labels, substantially as described. 70

5. A rotating table having a supporting device for holding a pile of labels, in combination with a device mounted at a fixed point for holding a bottle-nose during rotation of the bottle in contact with the top label, an automatic label-supply mechanism for advancing the pile of labels, and means for applying adhesive material to the labels, substantially as described. 80

6. The combination with a central device mounted at a fixed point for holding a bottle-nose during rotation of the bottle, of a rotating table carrying labels into position for application to a bottle, and a label-supply mechanism actuated by the rotation of the table, 90 substantially as described.

7. The combination with a central device mounted at a fixed point for holding a bottle-nose during the rotation of the bottle, and adhesive-applying means, of a rotating table for carrying labels into position to receive adhesive and into position for application to a bottle held by the central device, substantially as described. 95

8. The combination with a central device mounted at a fixed point for holding a bottle-nose during rotation of the bottle, and adhesive-applying means, of a rotating table for carrying piles of labels, and means actuated by the rotation of the table for advancing the 100 piles of labels as labels are withdrawn, substantially as described.

9. The combination with a supporting device for a block of labels secured together by adhesive at one end, of a rotating table having a central device mounted at a fixed point for holding the bottle-nose during rotation of the bottle, said device being mounted to rotate to permit the bottle to be moved over the block of labels from the free to the secured 110 ends of the labels during the rotation of the bottle, substantially as described. 115

10. The combination with a supporting device for a block of labels secured together by adhesive at one end, of a device mounted at a fixed point for holding the bottle-nose during rotation of the bottle, said device being mounted to rotate to permit the bottle to be moved over the block of labels from the free to the secured ends of the labels during the 120 rotation of the bottle, and a rotating table for carrying the block of labels into position for the application of a label to a bottle, substantially as described. 125

11. The combination with a supporting de- 130

vice for a block of labels secured together by adhesive at one end, of a device mounted at a fixed point for holding the bottle-nose during rotation of the bottle, and mounted to rotate 5 to permit the bottle to be moved over the block of labels from the free to the secured ends of the labels during the rotation of the bottle, an adhesive-applying roller, and a rotating table for carrying the block of labels 10 into position for receiving adhesive and for the application of a label to the bottle, substantially as described.

12. The combination with the cap V for holding an article for application of a label, 15 of means for adjusting said cap horizontally and vertically, and a label-holder for the label being applied, substantially as described.

13. A bottle-labeling machine provided with means for holding a bottle and means for 20 applying a body-label, and a central device mounted at a fixed point for holding the nose of the reversed bottle for application of a neck-label, substantially as described.

14. The combination with means for holding 25 a bottle or similar article, of a rotating ta-

ble for carrying labels into position for receiving adhesive and into position for receiving the body of the bottle and a moving belt for rotating the bottle in contact with a label, substantially as described.

30

15. The combination with a rotating label-carrier, of a support for a bottle or similar article, a rotating carrier, and a driven belt on said carrier for rotating the bottle in contact with a label, substantially as described.

35

16. A bottle-labeling machine having neck-labels with means for applying same and provided with a rotating table having a central device mounted at a fixed point thereon for holding the nose of a reversed bottle for application of a neck-label, substantially as shown and described.

40

In testimony whereof I have hereunto set my hand in the presence of two subscribing witnesses.
